UNITED STATES PATENT OFFICE.

GEORGE R. HINGELBERG, OF SHEFFIELD, ENGLAND, ASSIGNOR OF ONE-HALF TO JOHN BROWN AND COMPANY, LIMITED, OF SHEFFIELD, ENGLAND.

STEAM-GENERATOR.

SPECIFICATION forming part of Letters Patent No. 734,328, dated July 21, 1903.

Application filed August 9, 1902. Serial No. 119,025. (No model.)

To all whom it may concern:

Be it known that I, GEORGE ROBERT HINGELBERG, engineer, a subject of the King of Great Britain and Ireland, residing at 146 5 Burngreave road, Sheffield, in the county of York, England, have invented certain new and useful Improvements in Steam-Generators of the Marine Type, of which the following is a specification.

10 This invention relates to the setting of multi-tubular marine boilers provided with means for causing a draft of preheated air to be supplied to the furnaces by the inducing action of a fan or fans, which draws or draw the 15 products of combustion from the furnaces and discharge the said products up a chimney or into the atmosphere. In steam-generators of this type I, according to this invention, construct flues underneath the boiler and ex- 20 tending the whole length or nearly the whole length thereof and arranged in such a way that the greatest possible length of flue is in contact with the bottom of the boiler. The products of combustion from the furnaces 25 after passing through the heater by which air for the furnaces is preheated are led through ducts into one end of the said flues, the fan or fans drawing or forcing the said products through the said flues after they have passed 30 through the air-heater, the main portion of their remaining heat being during their passage through these flues imparted to the boiler, this improving the evaporative effect and tending to keep the boiler-shell at an 35 equable temperature during work.

I will describe, with reference to the accompanying drawings, an arrangement according to this invention wherein the products of combustion from the furnaces after 40 leaving the air-heater are caused to enter the suction side of the fan or fans and are discharged by the said fan or fans into the aforesaid flues, although it is to be understood that the fan or fans may be between the said 45 flues and the chimney or outlet to the atmosphere, so as to draw the said products through the said flues.

Figure 1 is a side elevation; Fig. 2, a plan, and Fig. 3 an end view with parts removed 50 from one-half.

A is the boiler, which may be of any suitable construction. It is shown as having two furnaces *a*, each with a flue leading into an uptake through which the products of combustion from the furnaces pass back through 55 tubes *a*² and thence into the casing *f* and through the tubes of the heater *B*, into which air to supply the furnaces enters by the openings *b* and passes between the tubes of the heater *B* and into the casing *b*², and thence 60 into the furnace.

C is a fan driven by the engine *C*² and arranged between the heater *B* and the flues *D* underneath the boiler.

E is the uptake or passage leading into the 65 chimney or into the atmosphere.

The products of combustion are drawn by the fan into the casing *f*, up through the tubes of the heater *B*, and through the passage *g* into the fan, by which they are forced down 70 the downcast *h* and through the passage *D*, provided with a wall *d*, so as to constitute zigzag flues, the said products of combustion as they pass through the said flues *D* imparting a great part of their heat to the bottom 75 of the boiler and then escaping through the flue *D*² and uptake *E*. These flues do not surround the entire shell, as in prior constructions, but are beneath the greater portion of the shell, exposing substantially the entire 80 lower surface of the boiler-shell to the products of combustion. In the drawings the entire shell is exposed to the flues below the horizontal center line passing through the fire-chambers, thus heating the shell at this 85 coldest portion and securing the equable heating of the boiler, producing equal expansion throughout and increasing the life of the boiler. Openings and doors may be provided, as at *d*², in any suitable positions for cleaning the flues *D*.

Instead of the fan being placed as shown it may be placed at the other side of the flues *D*, so as to draw the products of combustion therethrough instead of forcing them thereinto.

*E*² is a by-pass flue closed by a valve or damper at *e* when the fan is in action, the said valve or damper being capable of closing the passage *g* to the fan and opening the inlet to 100

the by-pass E² when the boiler is to be worked by natural draft.

I claim as my invention—

1. A marine boiler having a furnace provided with an uptake and return fire-tubes with a heater-easing having passages for air leading to the furnace and other passages for products of combustion leading from the fire-tubes, flues underneath the boiler exposed to substantially the lower surface of the boiler-shell and adapted to discharge the products of combustion into the uptake, an exterior flue or passage connecting the heater-easing with the said flues, and a fan interposed in said passage or flue adapted to cause the products of combustion to flow from the heater through the flues under the boiler to said uptake, substantially as described.

2. A marine boiler having a furnace provided with an uptake and return fire-tubes with a heater-easing having passages for air leading to the furnace and other passages for

products of combustion leading from the fire-tubes, flues underneath the boiler exposed to substantially the lower surface of the boiler-shell and communicating with the uptake, an exterior passage or flue connecting said lower flues with the heater-easing, a fan interposed in said exterior passage or flue for drawing the products of combustion through the heater-easing and forcing them through the flues under the boiler, and a branch passage or flue connecting said exterior passage with the uptake and provided with a valve or damper adapted to direct products of combustion directly to the uptake or through the flues underneath the boiler to the uptake, substantially as described.

In testimony whereof I affix my signature in presence of two witnesses.

G. R. HINGELBERG.
